Leonardo I. Leon, Massapequa, N. Y.

Application August 1, 1944, Serial No. 114,671

Term of patent 14 years

(Cl. D86—10)

To all whom it may concern:

Be it known that I, Leonardo I. Leon, a citizen of the United States, residing in Massapequa, in the county of Nassau and State of New York, have invented a new, original, and ornamental Design for a Curl Clip, of which the following is a specification, reference being had to the accompanying drawing, forming part thereof.

Fig. 1 is a plan view of a curl clip showing my new design, and

Fig. 2 is a perspective side view of the curl clip shown in Fig. 1.

I claim:

The ornamental design for a curl clip, substantially as shown.
